(No Model.)

T. W. McFADDEN.
HOPPER COCK FOR WATER CLOSETS.

No. 388,896.

Patented Sept. 4, 1888.

UNITED STATES PATENT OFFICE.

THOMAS W. McFADDEN, OF MUSKEGON, MICHIGAN.

HOPPER-COCK FOR WATER-CLOSETS.

SPECIFICATION forming part of Letters Patent No. 388,896, dated September 4, 1888.

Application filed October 5, 1885. Serial No. 179,068. (No model.)

To all whom it may concern:

Be it known that I, THOMAS W. McFADDEN, a citizen of the United States, residing at Muskegon, in the county of Muskegon and State 5 of Michigan, have invented certain new and useful Improvements in Hopper-Cocks for Water-Closets; and I do declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 This invention relates to an improvement in that class of inventions known as "hopper-cocks" for water-closets, the object being to simplify the construction of the same, to increase the durability of the valves by causing 20 them to have perpendicular contact with their seats, and to provide a trap which shall effectively prevent all escape of sewer-gas.

Therefore, in order to fulfill these objects, my invention consists in constructing the body 25 or main stem of the cock in three pieces, so that either one may be readily and easily duplicated.

It consists, also, in connecting the valves and lever attachment with one solid metallic stem 30 and in the peculiar relative location of the waste and discharge pipes, whereby the emission of sewer-gas is obstructed, and in the placing of the entire device directly below the seat of the water-closet in a perpendicular 35 position, thereby rendering its action automatic and dispensing with all pulley and cable connections; and the invention further consists in certain peculiarities of construction, as will be hereinafter specifically set forth and 40 claimed.

In the annexed drawings, illustrating my invention, Figure 1 is a vertical section through the device. Fig. 2 is a vertical end elevation, and Fig. 3 is a top plan view of the same.

45 Like letters of reference are used to designate like parts in the several views.

The main body of the cock consists, essentially, of the parts A B C.

A represents the central portion of this 50 main body, and is made of any suitable metal, brass, perhaps, being preferred. This portion

A is provided on each end with a suitable seat for the reception of the valves. It is also provided on one side, at or near the center, with an opening, a, into which passes the discharge 55 coming from the closet proper through the discharge-pipe.

B represents the lower portion of the cock, which is provided with an opening, b, through which water is supplied to the cock through 60 the water-supply pipe, and the part B is also provided with a horizontal bottom flange, D, of suitable proportions to enable the cock to be located firmly in its perpendicular position.

C represents the upper portion of the device 65 or cock, and it is provided with an opening, c, which opens into the waste pipe which carries away the waste from the closet. Thus the main body of the cock is formed of three parts, situated one above the other, the lower 70 one having the water-supply opening, the middle one having the discharge-opening, and the upper one having the waste-opening. The supply, discharge, and waste openings are all provided with outside threaded connections 75 for the purpose of attaching the pipes thereto.

The upper end of the part C is provided with a suitable cap, E, which is of such a diameter as to allow the valve-stem, with the upper valve attached, to be taken out when 80 required without disturbing the valve. Into the cap E is screwed the stuffing-box e. This stuffing-box is for the purpose of packing the stem, and also of acting as a guide for the same. The main body of the cock, as well as the cap 85 and stuffing-box, are all provided with inside and outside threaded connections for the purpose of fastening the whole device together. To the upper portion of the section C there is attached or cast solid therewith an arm or 90 standard, F, the upper end of which is conveniently formed with jaws, between which a lever, I, can rest and be fulcrumed therein upon a pivot.

G represents a solid metallic valve-stem, 95 upon which at suitable distances apart are arranged the collars g and the valves H. There are two of these valves H, an upper and a lower one, and they are so arranged upon the stem G at such a distance apart that when 100 either of them is closed upon its seat the other is sufficiently free from its seat to allow proper

space for the passage of water. These valves are secured in their places by means of screws and nuts provided on the stem for that purpose. To the top of the stem is securely fastened by suitable means, as a screw, a double-jawed joint, *h*, to which is connected one end of the lever *I*.

j represents a connecting-rod by which motion is communicated from the seat of the closet to the valves *H*. This rod is also preferably provided at its lower end with double jaws which inclose the joint *h*, the whole being then secured together by a pivot or pin upon which the several levers are movable; but it is evident that this particular method of connecting the levers may be departed from, and any suitable joints may be employed for connecting the weighted lever *I* and the seat-lever *j* with the stem which carries the valves. The lever *I* is pivoted between the jaws of the standard *F* by a pivot, *f*. At one end it is connected with the joint *h*, preferably in the manner shown in Fig. 2, by passing between the jaws of the said joint and being pivoted therein. The other end of this lever is provided with a weight, *O*, which is movable upon the lever and can be adjusted thereon to a greater or less distance from the stem *G*, so as to balance seats of variable sizes and weights. It is secured in any desired position by a set-screw, and it may be provided with a small perforated lug or eye, *o*, for the attachment of a cable or wire to enable the device to be operated at a distance when this method of operating is preferred.

In the drawings, Fig. 1, *N* represents the seat of a closet, and *M* a portion of the frame of the same. To this latter portion *M* is attached a guide, *k*, for keeping the lever *j* in an upright position. The operation of the hopper cock then is as follows: When the closet is in use, the movable seat *N* is depressed and comes into contact with the lever *j*, which in turn depresses the stem *G*, to which the valves *H* are secured. This operation of the valves closes the waste and opens the supply passage. It will be noted that this lower valve, *H*, is opened against the pressure of the water within the supply-pipe, and also that the weight attached to the lever *I* is raised in consequence of the depression of the stem *G*. Therefore when the weight is removed from the closet-seat the combined action of the weighted lever and the pressure of the water within the supply-pipe will reverse the movement of the stem and its valves and close the supply and open the waste passage. When the valves are in this position, it will be evident that the middle body or section of the cock will always contain a quantity of water on account of the difference in height

between the supply and waste pipes. Thus when the closet is not in use, this water will fill the cock in such a manner as to form a perfect preventative against the return of sewer-gas from the waste.

Valves of my particular form are probably not new, and I do not, therefore, lay claim to them, broadly. The construction and arrangement, however, of these valves on a solid stem placed perpendicularly below the closet-seat and operated directly by the movement of the seat is an improvement. Another point of merit in this arrangement lies in the relative position of the discharge and waste-water pipes, which creates an effectual sewer-gas trap when the closet is not in use; also, in consequence of the direct action of the device the supply-valve is closed by the pressure instead of against it, thus constituting a perfect and reliable water-tight joint, and consequently avoiding leakage.

Having thus described my invention, what I claim as new, and desire to secure by Letters Patent, is—

1. In a hopper-cock for water-closets, a solid stem carrying valves so situated thereon with reference to each other as that but one of them shall close upon its seat at a time, in combination with a perpendicular chamber constructed of three sections located one above the other, the lower one being provided with an opening for the entrance of the supply-pipe, the middle one being provided with an opening for the entrance of the discharge-pipe, and the upper one being provided with an opening for the entrance of the waste-pipe, the said valve-carrying stem being actuated by contact with the seat itself and by a weighted lever whose extremity is attached to the said stem, substantially as and for the purposes shown and described.

2. The combination of the perpendicular chamber *A*, having opening *a*, section *B*, having opening *b*, and section *C*, having opening *c*, the valve-stem *G*, carrying valves *H*, secured thereon by means of collars *g*, the standard *F*, the lever *I*, provided with weight *O* and fulcrumed at *f* in the standard and pivoted within the double-jawed joint *h*, attached to the upper extremity of the valve stem, and the connecting-rod *j*, secured at one end to the joint *h*, the other end connecting with the seat, all arranged and operating substantially as shown and described.

In testimony whereof I affix my signature in presence of two witnesses.

THOMAS W. McFADDEN.
